UNITED STATES PATENT OFFICE.

WILLIAM M. GOODWIN, OF CENTRAL SQUARE, NEW YORK.

VALVE-OPERATING MECHANISM FOR INTERNAL-COMBUSTION ENGINES.

Application filed September 16, 1924. Serial No. 738,019.

To all whom it may concern:

Be it known that I, WILLIAM M. GOODWIN, a citizen of the United States of America, of Central Square, in the county of 5 Onondaga, in the State of New York, have invented new and useful Improvements in Valve-Operating Mechanism for Internal-Combustion Engines, of which the following, taken in connection with the accompanying drawings, is a full, clear, and exact 10 description.

This invention relates to a valve-operating mechanism for internal combustion engines of the class set forth in my Patents 15 No. 1,270,941 of July 2, 1918, and No. 1,500,556 of July 8, 1924, in which a self-closing valve is adapted to be intermittently opened by means of a rotary cam shaft and suitable devices for transmitting motion 20 from the cam shaft to the valve.

In mechanisms of this character, considerable difficulty is experienced in preventing lost motion between the cam and valve and at the same time allowing the valve to 25 properly adjust itself to its seat, resulting in more or less of a tapping noise and partially due to the variation in length of the valve stem under different temperatures of the engine when at rest, and when in action.

30 The main object of my invention is to provide simple and efficient means capable of automatically taking up this lost motion, and preferably forming a part of the means for transmitting from the cam to the valve.

35 Another object is to provide the take-up device with a plurality of wedges of slightly varying lengths to conform to different distances between the end of the stem of the closed valve and operating cam therefor.

40 Other objects and uses relating to specific parts of the mechanism will be brought out in the following description.

In the drawings:

45 Figure 1 is a vertical sectional view of a portion of an internal combustion engine and cam shaft, together with one of the valves, and mechanism for transmitting motion from the cam shaft to the valve.

50 Figure 2 is a vertical sectional view taken in the plane of line 2-2, Figure 1, showing the means for operating the wedge to take up the lost motion.

55 Figure 3 is a perspective view of the detached wedge carrying sleeve.

55 In order that this invention may be clearly understood, I have shown a portion of an

internal combustion engine —1— having the usual valve seat —2— and guide —3— for one of the valves as —4—, which is self-closing by means of the usual spring —5— having its upper end seated against a portion of the engine frame —1— and its lower end engaged with a seat —6— on the valve stem as —4'—.

A cam shaft —7— is supported in any well-known manner some distance below the lower end of the valve stem —4'— and is provided with one or more cams —7'— adapted to be used as a primary source of power for intermittently opening the valve 70 —4— against the action of the spring —5—. The means for transmitting motion from the cam —7'— to the valve for opening the latter consists in this instance of a rock-arm —8— and sleeve —9—, which latter is supported for angular adjustment and axial movement in a bearing or bushing —10— on the engine frame —1—, the axis of the sleeve being parallel with, but at one side of the axis of the valve —4— a sufficient distance to bring different sides of the sleeve into registration with the lower end of the valve stem when the sleeve is adjusted rotarily to different positions for a purpose presently described.

80 The rock arm —8— is pivoted at —11— to a portion of the frame of the engine some distance to one side of the cam shaft —7— to rock vertically about an axis parallel with said shaft and has its other end provided 90 with an upturned extension —12— and a bearing roller —13—, the latter being in direct engagement with the face of the cam —7'— and directly over the axis of the shaft —7— whereby the rotation of the cam 95 effects a vertical reciprocatory movement of the extension —12— and a corresponding reciprocatory movement of the sleeve —9— and valve —4—.

100 The opposite ends of the sleeve —9— are provided with separate sets of inclined bearing faces —14—, —14'— and —14''— those of each set being disposed in axial alignment and tapered circumferentially in one direction to form a wedge interposed between the extension —12— and lower end of the valve stem —4'— for taking up lost motion between the valve-operating cam and valve and to compensate for variations in 110 the length of the valve stem due to varying temperatures thereof incidental to the heating or cooling of the engine.

The normal distance between the lower end of the valve stem and face of the cam when the valve is closed may vary slightly under different conditions beyond the range 6 of adjustment of any one wedge, and therefore the lengths of the wedges or distances between the inclined faces of each set are unequal to permit the proper adjustment of the valve for normal seating.

10 When any one of the particular wedges is positioned between the extension —12— and lower end of the valve stem —4'— it is automatically adjusted angularly or rotarily about its axis within the bearing —10— by 15 a coil spring —15— arranged axially therein and having one end connected to an end partition —17— and its other end connected to a collar —16— which is tight on the end of a bracket —18—, the latter being secured by a bolt —19— to an upward extension of the bushing —10—, and therefore in fixed relation to the frame —1— and sleeve —9—.

20 The spring —15— is placed under tension 25 to exert an angular rotation of the sleeve —9— in the direction of the shorter end of the wedge so as to take up lost motion between the cam —7— and valve —4— and thereby to compensate for inequality at 30 slight variations in length of the valve stem due to varying temperatures thereof, it being understood that the spring may also exert an endwise pressure upon the sleeve —9— to hold it in engagement either with the extension —12— or lower end of the valve stem —4'—, and that this spring is relatively light as compared with the valve-retracting spring —5—, so that the latter may function freely in closing the valve against 35 its seat —2— without appreciable resistance by the tension of the spring —15—.

Operation.

40 When the engine is at rest and the valve 45 is at approximately normal temperature the sleeve —9— is adjusted by hand to bring the proper wedge between the extension —12— and lower end of the valve stem 4' with said extension and valve stem in contact with substantially the central portions 50 of the inclined faces of the wedge thus permitting slight rotary movement of the sleeve in reverse directions as may be required to 55 prevent lost motion between the cam and valve.

During the operation of the valve by the rotation of the cam —7— the upper end of the extension —12— will have a slight movement along the adjacent inclined bearing face —14— due to the fact that the pivot 60 —11— for the arm —8— is rotated some distance to one side of the axis of the cam shaft —7—, which sliding movement, together with the slight incline of the bevelled faces of the wedge tends to slightly 65

release the endwise pressure upon the sleeve, and this release permits the spring —15— to take up any lost motion due to such sliding movement, while on the other hand the return movement of the extension —12— down the incline would tend to move the sleeve rotarily in the same direction in case the take-up movement of the sleeve by the spring —15— should tend to prevent the proper seating of the valve, but in any event 75 the seating pressure of the valve by the spring —5— together with the inclined faces of the wedge tends to move the sleeve angularly against the action of the spring —15— so that these two factors operate to maintain a tight connection between the cam and valve to prevent lost motion between those parts.

I claim:

1. The combination with a self-closing 85 poppet valve for internal combustion engines and a rotary cam, of means including a wedge rotatable about an axis parallel with and at one side of the axis of the valve for transmitting motion from the cams to the valve and for taking up lost motion between said cam and valve.

2. The combination with a self-closing 90 poppet valve and a rotary operating cam therefor, of means for transmitting motion from said cam to the valve including a cam-operated member and a wedge for transmitting motion from said member to the valve, and adjustable about an axis parallel with and at one side of the axis of the 95 valve to take up lost motion.

3. The combination with a self-closing 100 poppet valve and means for intermittently opening the same, including a wedge, and means for automatically adjusting the wedge about an axis parallel with and at one side of the axis of the valve to take up 105 lost motion.

4. The combination with a self-closing 110 poppet valve and means for intermittently opening the same including a wedge rotatable about an axis parallel with and at one side of the axis of the valve and spring-actuated in the direction of its smaller end 115 for taking up lost motion.

5. The combination with a self-closing 120 poppet valve and means for intermittently opening the same including a sleeve adjustable rotarily about an axis parallel with and at one side of the axis of the valve and provided with bearing faces at both ends inclined circumferentially in the same direction.

6. The combination with a self-closing 125 poppet valve and cam shaft of an internal combustion engine, of a rock arm actuated by the cam, and a wedge adjustable rotarily about an axis parallel with and at one side of the axis of the valve for transmitting motion from the rock-arm to the valve.

7. The combination with a self-closing poppet valve and cam shaft of an internal combustion engine, of a rock-arm actuated by the cam, and a wedge adjustable relatively about an axis parallel with and at one side of the axis of the valve for transmitting motion from the rock-arm to the valve, said wedge being spring-actuated in one direction to compensate for varying distances between the valve and rock-arm.

10 In witness whereof I have hereunto set my hand this 30th day of August, 1924.

WILLIAM M. GOODWIN.
